United States Patent Office

Des. 227,577
Patented July 3, 1973

227,577

WALL SWITCH

Noel Mayo, Philadelphia, Pa., assignor to Lutron
Electronics Co., Inc., Coopersburg, Pa.

Filed July 27, 1971, Ser. No. 166,651

Term of patent 14 years

Int. Cl. D13—03

U.S. Cl. D26—13 B

FIG. 1 is a front perspective view of a wall switch showing my new design.

FIG. 2 is a front plan view of FIG. 1.

FIG. 3 is a top plan view of FIG. 1.

FIG. 4 is a side plan view of FIG. 1.

FIG. 5 is a front perspective view of a second embodiment of the new design.

FIG. 6 is a top plan view of FIG. 5.

I claim:

The ornamental design for a wall switch, as shown and described.
